UNITED STATES PATENT OFFICE.

SAMUEL E. TURNER, OF WICHITA FALLS, TEXAS, ASSIGNEE TO PANHANDLE REFINING COMPANY, OF WICHITA FALLS, TEXAS.

METAL-TRANSOM CUSHION-BLOCK CONTAINER.

Application filed January 19, 1926. Serial No. 82,308.

My invention relates to tank cars, and particularly to that character or type of cars employed for railway transportation of liquids in bulk, and comprising a horizontally disposed cylindrical tank supported upon an underframe which, in turn, is mounted on wheeled trucks. More specifically stated, the invention has to do with the connection between the underframe and the tank, and comprises the combination with said underframe of certain elements which I have called a metal transom cushion block container. The objects of the invention are to provide a simple and efficient method of securing cushion blocks in place upon the transoms or transverse bolsters of the trucks, said cushion blocks receiving and sustaining the body of the tank, while permitting movement thereof due to expansion and contraction of the metal; also to accomplish the first object without the use of bolts, screws, lag screws, nails or any other agency whereby the fiber of the wood cushion block is undisturbed; and to provide a simple and efficient method for the renewal of the cushion blocks.

Briefly stated, I attain my objects by providing an extended bed plate or holder formed of sheet metal with parallel spaced longitudinal corrugations or channels formed in it, so that when the ends of the plate are laid upon the bolsters or transoms of the underframe, the corrugations will overlie and clear the main frame or transom frame rivets. These corrugations also serve to divide the bed plate into parallel longitudinal sections, each adapted to receive and hold one wooden cushion block, longitudinal movement of which is prevented by means of short angle sections riveted across the ends of the respective channel sections between the corrugations.

My invention is illustrated in the accompanying drawings, in which—

Fig. 1 is a plan view of the bed plate or holder detached;

Fig. 2 is an end view of the same;

Fig. 3 is a cross sectional view of the tank and center sill showing one transom or bolster in full lines of my invention applied to one side of the same.

Referring to the drawings, I have not illustrated the entire structure of a tank car, as the general features of the same are well understood, and are illustrated in numerous

Letters Patent, as for example those granted to E. Posson, May 5, 1914, No. 1,095,350, to which reference may be had for an understanding of the general type of tank car to which my invention is applicable.

In the drawings, C designates the tank (see Fig. 3) which rests upon an underframe composed of a longitudinal sill T and two or more bolsters or transoms T'. The longitudinal sill is of standard construction, comprising the parallel side webs t—t' with upper and lower angles forming channels, and upper and lower plates bridging the same and riveted thereto. The transom T is of standard construction, having a center web or parallel webs, with transverse head and foot flanges, the upper plate t² of the same extending across and being riveted to the angle head of the transom itself and also to the upper flanges of the sill members. An extension of this plate t² receives the bed plate A, which is of a length sufficient to reach from one bolster to the other, and is riveted thereto at a² with counter sunk head rivets a³ (see Fig. 3). The bed plate or holder A as shown carries three cushion blocks B, B', B², and therefore has four parallel channels or corrugations a formed in it, leaving between them sectional spaces with a smooth surface delimited at the ends by angle plates a' riveted across the width of the respective sections. The wooden cushion blocks B, B', B² are placed in the sections between corrugations, as indicated by dotted lines in Figs. 1 and 2, and shown in full lines in Fig. 3, being held against end displacement by the angle plates a' and against lateral displacement by the corrugations a. In Fig. 3, the transom plate rivets are shown at t³ underlying the channels or corrugations a.

Overlying the sill members t—t' are two fixed longitudinal cushion blocks C', the surfaces of which together with the surfaces of the cushion blocks B, B', B², curve in a cylinder corresponding with the cylindrical surface of the tank C. The tank rests vertically upon these blocks C' and lateral thrust is taken up by the blocks B, B', B² which also carry their appropriate part of the weight. K in Fig. 3 conveniently represents the train pipe, controlling brakes or signals, or both. It might be stated that in practice the bed plate A extends at each end one inch beyond the transom cover plate t².

What I claim is:

1. In a tank car, an underframe having transoms, a tank body, and a support for said tank body extending longitudinally thereof from one transom to another and comprising a bed plate corrugated to form a plurality of panels, longitudinal cushion blocks resting between the corrugations on said panels, and means carried by said bed plate to prevent longitudinal displacement of said cushion blocks.
2. In a tank car, an underframe having transoms, a tank body, a support for said tank body comprising a longitudinal corrugated bed plate having its ends resting upon and riveted to said transoms, longitudinal cushion blocks carried on said bed plate between said corrugations, and end stops secured to said bed plate to prevent longitudinal displacement of said cushion blocks.
3. In a tank car, an underframe composed of a longitudinal sill, and transverse bolsters or transoms having vertical webs and head and foot flanges, a tank body, and an intermediate support for said tank body comprising a bed plate with parallel longitudinal corrugations forming panels or channels therein, and spaced apart so as to overlie and clear the head flange rivets of the transom, means for securing said bed plate to the transoms in the spaces between the corrugations, in such manner as to leave a smooth surface, cushion blocks extending longitudinally of the bed plate in said several panels or channels, with end plates to prevent longitudinal displacement of said blocks.
4. In a tank car, an underframe, a tank body, and a support for said tank body on said underframe, said support comprising a unitary metal bed plate or holder resting upon and secured to the underframe and a plurality of parallel wooden cushion blocks carried loosely on said bed plate without securing means, said bed plate being provided with end limiting stops and intermediate separators to prevent longitudinal or transverse displacement of said cushion blocks, respectively.
5. In a tank car, an underframe, a tank body, and supports for said tank body secured to said underframe, each support comprising a unitary rectangular metal bed plate or holder resting longitudinally upon and riveted to the underframe, portions of the metal of said bed plate or holder being bent up along a plurality of parallel lines dividing the holder into parallel longitudinal panels, and wooden cushion blocks lying one in each panel with said projections between them and on opposite sides thereof, said bent up portions or projections being so formed and located that they overlie and leave space beneath them for the heads of rivets securing the device to the underframe.
6. A metal transom cushion block container or cradle comprising a unitary integral rectangular sheet of metal, divided into a plurality of parallel longitudinal panels, with integral portions of the metal formed up between each two adjacent panels to form separators therefor, metal flanges also bent up at the ends of the respective panels, with a plurality of wooden cushion blocks supported on the respective panels of said container, and positioned thereon by said separators and end flanges, respectively.

In testimony whereof I hereunto affix my signature.

SAMUEL E. TURNER.
